Mac V. Dohmen, ATTORNEYS.

UNITED STATES PATENT OFFICE.

GUSTAV MEIER, OF NEW YORK, N. Y.

CAN OPENER.

Application filed January 4, 1927. Serial No. 158,952.

This invention relates to can openers and has for its object to provide a device that can be conveniently handled in the household for opening tin cans of any size and shape.

- 5 With this object in view my invention consists in the novel construction, combination and arrangement of parts as will be herein-after more fully described and defined in the appended claims.
- 10 In the accompanying drawing which constitutes part of this specification and in which similar reference characters denote corresponding parts Fig. 1 is a front elevation of my device; Fig. 2 a side elevation 15 thereof; Fig. 3 a cross-section on line 3—3 of Fig. 2 and Fig. 4 a front elevation of a modified form of construction.

The device comprises a rigid upright support 10 having a flat front face and which 20 at its lower end is U shaped as at 10¹. The lower forwardly projecting part of said U shaped part carries a vertically working clamping bolt 11 whereby the support can be conveniently and easily clamped to a table 25 or the like. The upper portion of the support is centrally and longitudinally slotted as at 10^a to adjustably and pivotally support a cutter or knife 12. This cutter or knife consists of a comparatively long arm or 30 handle which at its lower end is formed with laterally projecting curved wings 12¹ the outer circumferential edges 12² of which are sharpened to constitute blades. The lower edge of the said blades are circularly grooved 35 as at 12³ to form pointed tips 12⁴ and an intermediate ear 12⁵. The latter bears a screw bolt 13 adapted to be passed through the recess 10^a of the support. 14, 15 are washers inserted between the arm 12 and 40 support 10 and between the support and a thumb nut 16 whereby the arm is pivotally suspended from said support and can be clamped in position after its adjustment to the desired elevation.

45 To operate my device the tin can C to be opened, is placed on the table T close to the support 10 and the knife adjusted in the support so that when the arms are swung to and fro like a pendulum in opposite directions 50 around its pivot the two blades will alternately be forced through the top of the can and produce incisions therein. During this cutting operation the can is guided and fed by hand.

In the modified construction shown in Fig. 4, the knife has a single blade 12⁶ the cutting edge of which is formed around the curved bottom edge of the wing as at 12⁷. The opposite wing 12⁸ is adapted to serve as a gripper and to this end its bottom edge is roughened or formed with ridges as at 12⁹. The pivotal point of the arm 12^a formed with this modified knife is arranged eccentrically as at 12¹⁰ so that as the arm 12^a is swung to the left (according to Fig. 4) the blade 12⁷ will first pierce the top of the can with its tip 12¹⁰ and then produce an incision in the forward direction. When the arm is swung in the reverse direction the gripper 12⁹ will engage the can and feed it rearwardly or 70 toward the blade.

What I claim is:

1. A can opener, comprising an upright support adapted to be removably attached to a table or the like and having a continuous longitudinal slot, and a comparatively long lever arm pivoted in said slot so as to be adjustable therein in a continuous manner, and formed with a curved cutting edge arranged laterally of the pivotal point of said arm, a portion of said cutter being roughened whereby in one position automatic feeding of the can being cut will result.

2. A can opener, comprising an upright support adapted to be removably attached to a table or the like and formed with a continuous longitudinal slot, a comparatively long lever arm pivoted in said slot so as to be adjustable therein in a continuous manner and formed with a curved cutting edge projecting laterally relative to the pivotal point of said arm, a portion of said cutting edge being serrated to form a can feeding means.

3. A can opener comprising an upright support adapted to be removably attached to a base, and formed with a longitudinal slot, a comparatively long arm provided at one end thereof, with a curved laterally extending cutting edge formed with a roughened portion, said arm being pivoted at a point intermediate its end to a pivot slidably adjustable in said longitudinal slot, whereby when said arm is given a pendulous motion about said pivot, alternate cutting and automatic feeding of the can to be cut will result.

4. A can opener comprising an upright support adapted to be removably attached to a base, a comparatively long arm provided

at one end thereof, with a laterally extending cutting edge and automatic feeding means on said cutter whereby alternate cutting and automatic feeding of the can to be cut will result.

5. A can opener comprising an upright support adapted to be removably attached to a base, an arm adjustably pivoted thereto and

provided at one end thereof with a laterally extending cutting edge, and having feeding 10 means on said cutting means whereby alternate cutting and automatic feeding of the can to be cut will result.

In testimony whereof I affix my signature.

GUSTAV MEIER.
